CLAIM

The ornamental design for a container cover or the like, substantially as shown.

DESCRIPTION

FIG. 1 is a top perspective view of a container cover or the like showing my new design;

FIG. 2 is a top plan view thereof;

FIG. 3 is a bottom plan view thereof;

FIG. 4 is a side elevational view thereof;

FIG. 5 is an end elevational view thereof;

FIG. 6 is another end elevational view thereof; and

FIG. 7 is a cross-sectional view thereof taken along line 7—7 of FIG. 5.

FIG. 1

FIG. 2

FIG. 3

FIG. 4

FIG. 5

FIG. 6

FIG. 7
